UNITED STATES PATENT OFFICE.

HOWARD G. WIDMER, OF BROOKLYN, NEW YORK, ASSIGNOR TO ARKELL SAFETY BAG COMPANY, OF NEW YORK, N. Y., A CORPORATION OF NEW YORK.

TUBE OR BAG AND METHOD OF MAKING THE SAME.

Application filed July 12, 1920. Serial No. 395,654.

To all whom it may concern:

Be it known that I, HOWARD G. WIDMER, a citizen of the United States, and a resident of the borough of Brooklyn, county of 5 Kings, and State of New York, have invented certain new and useful Improvements in Tubes or Bags and Methods of Making the Same, of which the following is a specification, reference being had to the accompanying drawings, which form a part hereof.

This invention relates to a paper tube or bag and the method of making the same. The primary object of the invention is to provide a paper bag for use in compound 15 paper-textile bags of the type shown in Arkell Patent 565,587, which paper bag will be stretchable over its entire surface.

To attain this object, I have devised a bag which is provided near the top with a free 20 pleat. I have also improved the mode of manufacture of these bags so that the seam which ordinarily has heretofore been at one edge of the bag, is now placed along, or near, the middle of one of the sides of the bag. 25 The edge seam in the paper bag has been objectionable as the greatest strain on the paper bag came at this point when the textile bag was lifted by the usual ears. This is especially true when the paper bag is 30 provided with a sewed seam.

Another object of the invention is to improve the fastening of the mouths of the paper and textile bags whereby the usual ears are done away with. The bag will then be 35 substantially symmetrical end for end.

Other objects of the invention will appear as the description proceeds.

In the drawings, I have shown one form 40 of paper bag, a method of making the same, and the mode of assembly of the paper and textile bags.

It is desired that these drawings shall be considered as illustrative of the invention rather than limiting the same.

45 In the drawings, Fig. 1 illustrates a tubular article made of crinkled paper and having a seam along one edge thereof.

Fig. 2 illustrates a fixed cylindrical former over which the tube shown in Fig. 1 is 50 adapted to be drawn.

Fig. 3 illustrates the tube in such position, with a movable die adjacent.

Fig. 4 illustrates the complete formation 55 of the pleat, the former and die being yet in place.

Fig. 5 illustrates a bag after it has been removed from the pleating devices and after the bottom has been sewed and folded.

Fig. 6 is a section on the line 6—6 of Fig. 5 showing the empty bag with the free pleat. 60

Fig. 7 illustrates a filled paper bag within a textile bag and shows the mode of fastening or closing the mouths of the bags.

Fig. 8 is a section on the line 8—8 illustrating the disposition of the seams in the 65 paper and textile bags respectively.

The paper tube 10, which has been made from a sheet by folding the sheet centrally, shown in Fig. 1, has, along one edge, a seam 11, which may be either sewed or pasted. 70 The tube, or bag, is here to be considered as empty and flat. In order to provide the tube, or bag, with a pleat near an open end, the tube, or bag, may be drawn over a suitable form which is shown in Fig. 2 75 as cylindrical. The form is tubular and has cylindrical portions 12 and 13 of different diameters. The cylindrical portion 13 extends inside the portion 12 for a short distance to provide an annular recess 14. 80 When the paper tube or bag has been drawn over the form, the free end of the bag will assume substantially the position shown at 15 in Fig. 3, i. e., it will contract. A cylindrical die 16 is passed down over the contracted part of the paper tube. The die 16 is of proper diameter so that it will pass outside the cylindrical portion 13 and into the recess 14. When the die passes into this recess, it carries the paper tube 85 along with it, whereupon the parts assume the position shown in Fig. 4, the tube being pleated at 17, the folds being at 17^a and 17^b. The die may then be removed.

When the tube is in the form shown in 90 Fig. 1, the seam is at the edge. In order that the seam may now come in the middle of one side of the bag, it is only necessary that the operator should grasp the tube in the proper position when the tube is drawn 95 off the former. The tube will now be as shown in the upper part of Fig. 5, in which the seam is at one side of the collapsed tube instead of at one edge.

It is to be understood that the above is 100 only one of the many appliances which may be employed to pleat the bag in this fashion. The operator may use his fingers instead of the cylindrical die 16.

To make a bag, the tube is then sewed 110

or pasted at the bottom at 18 and may or may not be folded over, as desired. It is preferred, however, that it should be folded over as this will re-inforce the bottom seam 5 and permit the bag to yield in service. The folded-in edge of the paper is indicated at 18^a.

The completed paper bag is shown in Fig. 5. This bag is intended for use within an 10 outer textile bag. It is inserted by hand into this textile bag and filled in the usual manner. After the bag is filled, it may be closed, either in the usual fashion by rolling down and sewing together the mouths of the 15 bags, leaving the usual ears for handling the same—but I prefer to pass the filled bag through a sewing machine which will securely sew the textile and paper bags together as shown in Fig. 7 at 19. The position taken by the folds 17^a and 17^b of the 20 pleat 17 will then assume some such position as shown. It is clear that when the filled bag is grasped at the upper edge thereof, the pleat 17 will spread, permitting longitudinal 25 stretchability of the paper bag relative to the textile bag. Heretofore, the weakest part of the combined paper textile bags has been at the top, as the crinkled paper from which the paper bag is made 30 does not provide longitudinal stretchability. It was also customary to have the side seam 11 adjacent the seam of the textile bag. When, however, the improved bag shown in Fig. 5 is used in a textile bag, the seam 11 35 of the outer bag comes along the middle of one side of the textile bag, as shown in Fig. 8. In this zone, the load placed upon the seam 11 is very much less than the load which would be placed upon it were it on 40 the side of the bag, as heretofore.

While I have shown my invention in what I believe to be the most efficient and desirable form, it will be understood that various changes may be made without departing 45 from the scope of the invention.

I claim:

1. An article made of crinkled paper having a free pleat near an open end thereof whereby longitudinal extensibility is permitted.

2. A bag made of crinkled paper having a free fold at the bottom and having a free pleat near the top thereof whereby longitudinal extensibility is permitted.

3. An article made of a single sheet of crinkled paper by seaming two opposite margins to form a tube, and closing one end of the tube to form a bag, said bag having said seam along a middle portion of one side thereof, and being further provided with a free transverse pleat, remote from the end thereof.

4. An article made of a single sheet of crinkled paper by seaming two opposite margins to form a tube, and closing one end 65 of the tube to form a bag, said bag having said seam along a middle portion of one side thereof, and being further provided with a free transverse pleat near the open end thereof and also with a free fold at the 70 closed end thereof.

5. An article made of a single sheet of crinkled paper by seaming two opposite margins to form a tube, and closing one end of the tube to form a bag, said bag having 75 said seam along a middle portion of one side thereof, and being further provided at the closed end thereof with a free fold.

6. A circumferentially stretchable crinkled paper article of the class described, 80 provided with means to permit longitudinal extensibility near an open end thereof, said means comprising a free pleat.

7. A circumferentially stretchable crinkled paper article of the class described, 85 provided with means to permit longitudinal extensibility near an open end thereof, said means comprising a free side-pleat.

8. A circumferentially stretchable crinkled paper bag provided with means to permit longitudinal extensibility near an open 90 end thereof, said bag also having a free fold at the closed end thereof, and a longitudinally seamed portion, which seamed portion is also longitudinally extensible.

9. The combination with an outer textile bag having a side seam along one edge thereof, of an inner crinkled paper bag whose crinkles are longitudinal, said bag being provided with means to permit longitudinal 100 stretchability independent of the textile bag near the top thereof.

10. The combination with an outer textile bag having a side seam along one edge thereof, of an inner crinkled paper bag 105 whose crinkles are longitudinal, said bag being provided with means to permit longitudinal stretchability independent of the textile bag near the top thereof, said paper bag being further provided with a longitudinal 110 seam disposed medially in one of the sides of the bag, when flat, whereby, when the bag is filled, the seam is subjected to a minimum stress.

11. A combined inner paper and outer textile bag wherein the mouths of said bags are sewed together, and the paper bag is provided with means to permit circumferential extensibility, and with means to permit longitudinal extensibility.

This specification signed this 9th day of July, A. D., 1920.

HOWARD G. WIDMER.
